UNITED STATES PATENT OFFICE.

WILLIAM L. DENCH, OF PELHAM, NEW YORK, ASSIGNOR TO ELLIOTT-FISHER COMPANY, OF HARRISBURG, PENNSYLVANIA, A CORPORATION OF DELAWARE.

KEY-LOCKING MECHANISM FOR WRITING AND ADDING MACHINES.

1,113,315.

Specification of Letters Patent.

Patented Oct. 13, 1914.

Application filed July 7, 1909. Serial No. 506,318.

To all whom it may concern:

Be it known that I, WILLIAM L. DENCH, a citizen of the United States of America, residing at Pelham, in the county of Westchester and State of New York, have invented certain new and useful Improvements in Key-Locking Mechanism for Writing and Adding Machines, of which the following is a specification.

10 This invention relates to combined type-writing and adding machines, and more particularly to a novel mechanism for automatically locking the numeral keys during retraction across the column.

15 By way of premise, it may be stated that the invention is designed to constitute a part of the equipment of what is known to commerce as the Elliott-Fisher writing-adding machine, in which a flat platen or down-

20 wardly printing typewriter is equipped with a computing device or register which is relatively stationary with respect to a master actuating means movable with the typewriter carriage and operated from the numeral keys. In this machine certain mecha-

25 nisms of the register are reset automatically by the retraction of the typewriter carriage across the column. Therefore, in order to prevent the operation of the computing de- 30 vice or register at a time when the mechanism thereof is not in proper operative condition, the machine includes provision for automatically disconnecting the numeral keys from the master actuator during the 35 retractile movement referred to. Notwith- standing this disconnection of the keys and adding mechanism, it may be possible to operate the numeral keys before the proper retractile movement has been completed,

40 thereby printing a number in the column without accumulating the same in the register. By reason of this possibility it has been proposed to dog the carriage against forward movement until the proper retract-

45 tile movement thereof has been completed, such dogging means being shown in my co- pending application No. 438,835, and serv- ing to apprise the operator of the improper manipulation of the machine by the failure 50 of the carriage to feed forward when the improperly operated key rises. While this dogging means is an effective safeguard, it is apparent that a single digit may be print- ed before the operator is apprized of his 55 error.

The object of the present invention, therefore, is to provide means whereby, when the retractile movement of the carriage across the column is commenced, the numeral keys will be automatically locked and will remain locked until the requisite retractile movement necessary to the proper position- 60 ing of the mechanism has been completed, at which time the keys will be automatically unlocked to permit the normal operation of 65 the machine.

A further object of the invention is to place the key locking mechanism under the control of the setting device for the key connecting mechanism so that the key lock- 70 ing means will be rendered entirely inoper- ative when the key connecting mechanism is unset to permit the use of the typewriter independently of the adding mechanism.

To the accomplishment of these objects, 75 the preferred embodiment of the invention resides in that construction and arrangement of parts to be hereinafter described, illustrated in the accompanying drawings, and succinctly defined in the appended 80 claims.

In the accompanying drawings—Figure 1 is a vertical section through so much of an Elliott-Fisher writing-adding machine as is necessary to illustrate my invention 85 applied thereto. Fig. 2 is a plan view of the same with parts removed. Fig. 3 is a vertical section through a portion of the ma- chine with the key locking mechanism in its 90 unlocked position. Fig. 4 is a similar view 95 with the keys locked. Fig. 5 is a detail per- spective view of a portion of the key lock- ing mechanism detached. Fig. 6 is a group 100 of detail views of other elements of the key locking mechanism. Fig. 7 is a rear eleva- tion of a portion of the carriage showing cer- 105 tain elements of the key locking mechanism. Fig. 8 is a perspective view designed to illustrate both the key connecting and the key locking mechanisms and to show their relation, and Fig. 9 is a detail view of a modified form of the lever 52, the modi- fication consisting in omitting the projec- 110 tion 43 and providing a vertically disposed slot 48 which receives the abutment 50 in the rearward position of the setting plate 47.

The Elliott-Fisher machine.—The Elliott-Fisher machine to which my invention is shown applied includes in its organization a flat platen 1 over which travels longitu-

nally for line spacing a machine frame 2 upon which travels transversely of the platen for letter spacing a carriage 3. Supported on and movable with the carriage 3 is printing mechanism in the form of type arms 4 connected by draw-wires 5 to key levers 6 fulcrumed in the casing 7 of the carriage and connected to the stems 8 of letter and numeral keys 9 and 10, the former being indicated in dotted lines in Fig. 1. The carriage 3 advances step-by-step under the impulse of carriage propelling mechanism, not shown, and this letter space movement is controlled by escapement mechanism 15 operated from the keys in a manner familiar to those skilled in the art and therefore requiring no specific disclosure. Likewise the machine is equipped with inking mechanism and other appurtenances which, being well understood, have been omitted from the drawings.

The adding mechanism.—Since the machine is designed to add as well as record columns of numbers, a register or computing device 11 is mounted in rear of the carriage upon a supporting bar 12 carried by brackets 13 secured at the upper rear corner of the frame 2. The register 11, so far as my present invention is concerned, may be of any approved form, but a construction available for use is shown in Patent No. 825,494 to J. A. Smith and also in the copending application No. 308,279 to Laganke and Smith. The register includes, as usual, a series of denominational members or wheels 14 occupying progressive denominations and associated with suitable carrying mechanism, the digits from 1 to 9 being displayed upon the peripheries of said wheels, or, as in the form of register shown, upon registering wheels 15 geared to the wheels first named, one digit on each wheel being displayed opposite the sight opening at the front of the register. The denominational wheels 14 of the register 11 are operated by a master wheel 16 movable with the carriage 3 to engage successive number wheels and operated from the numeral keys 10 of the typewriter through the medium of a series of operating connections one of which, 17, is indicated generally in Fig. 1. The several connections 17 are alike, with the exception that they are graduated as to the degree of transmitted movement so that the master wheel 16 is rotated from one to nine units of movement by the respective numeral keys, for the purpose of accumulating in the register the value represented by the key from which it is operated and by the digit which is printed upon the depression of said key. The master wheel and its operating connections are fully disclosed in Patent No. 829,971 to Laganke and Smith, to which reference is made for a more complete disclosure than is thought necessary for present purposes.

The key connecting mechanism.—The operating connections 17 between the keys 10 and the master wheel 16 include swinging links 18 adapted to be operatively connected to the key stems 8 by separable connections 19. The purpose of this arrangement is to enable the numeral keys of the typewriter to be entirely disconnected from the adding mechanism under normal conditions and to be connected therewith when the printing point of the typewriter is within the normal or adding field and the adding mechanism is in condition for operation. This connection between the adding mechanism and keys is ordinarily controlled by what is known as automatic key connecting mechanism, which is fully disclosed in Patent No. 863,232 to John A. Smith, but will be briefly described since this mechanism enters into combination with the novel features to be hereinafter referred to.

Mounted in the casing 7 of the carriage is what is known as a key connecting yoke 20 engaging longitudinal slots in the several links 18 and adapted to be swung for the purpose of shifting the links 18 into and out of engagement with the stems 8 of the numeral keys. The yoke 20 is operated by a yoke-operating lever 21 with which is associated a shiftable setting plate 22 carrying an abutment roller 23 shiftable with the plate 22 to or from a position above the rear end of what is known as an intermediate lever 24 fulcrumed in the carriage casing, as shown in Fig. 8, and having its rear end 100 pretruded through the rear wall of the casing and engaged by an arm 25 fulcrumed upon a screw stud 26 and normally held in an elevated position by a spring 27. Also fulcrumed on the stud 26 is what is known as the key connecting arm 28 resting upon an adjustable abutment 29 on the arm 25 and having at its free end a cam 30 adapted to ride under a plate or ledge 31 which projects beyond the lower front corner of the register, as shown, see particularly Figs. 7 and 8.

It will be seen that if the links 18 are in their normal disconnected positions, shown in Fig. 4, the forward movement of the carriage will cause the cam 30 to be engaged with and depressed by the register plate 31, thus depressing the arm 28 and with it the arm 25, the latter in turn depressing the rear end of the lever 24 which, by engagement with the abutment roller 23, will elevate the rear end of the yoke-operating lever 21 which will swing the yoke 20 forwardly and thus cause the latter to move the links 18 into connection with the key stems, see Fig. 1.

In addition to the parts recited the key connecting mechanism includes means whereby it may be set for automatic operation when the cam 30 engages the plate 31 or un-

set so that the keys will remain disconnected from the adding mechanism while the adding field, as well as other portions of the work sheet, are being traversed. This setting mechanism includes a setting lever 32, see Figs. 2 and 8, fulcrumed at 33 and connected at one end to a setting key 34 and at its opposite end to the setting plate 22.

By shifting the key 34 the abutment roller 23 may be moved to "add" position, see Fig. 8, in which event the keys will be automatically connected when the master wheel comes opposite the register, or to the "total" position, see Fig. 3, in which event the depression of the arm 30 by the plate 31 will not effect the operation of the lever 21 and as a consequence no automatic connection of the keys with the adding mechanism will be effected when the column is reached.

The key locking mechanism.—I now come to that portion of the structure which embraces the novel features introduced by me for the accomplishment of the recited objects. Journaled in bearings 35 upstanding from the bottom of the casing 7 is a rock shaft 36 provided with a series of laterally disposed longitudinally adjustable stops 37 which may be in the form of screws screwed into the shaft 36 and secured by lock nuts 38. Normally the stops or locking members 37 occupy the positions shown in Fig. 3; but by the oscillation of the shaft 36, these stops may be raised to vertical positions, as shown in Fig. 4, which will present them immediately under the stems 8 of the numeral keys 10 to lock the latter against depression. While the shaft 36 may be rotated by hand, or by any suitable means, the present embodiment of the invention comprehends the automatic operation of the locking shaft 36 to lock the keys when the carriage is retracted across the column or adding field so that the keys cannot be operated during such retraction of the carriage as is necessary in the machine here shown to restore certain elements, to-wit, the carrying mechanism, to normal position.

In the machine as heretofore constructed and as fully described in Patent No. 863,232 already referred to, the cam 30 not only rides under the register plate 31 upon the forward movement of the carriage, but rises and rides over the plate as the carriage is retracted, see for instance Fig. 3. The arm 28 is therefore available to operate the key locking mechanism and I have devised a connection between the arm 28 and the shaft 36 whereby, when the cam 30 rises over the plate 31, the shifting of the arm 28 thus effected will rock the shaft 36 from its normal position, shown in Fig. 3, to its locking position, shown in Fig. 4, the keys being maintained in this locked condition until the retractile movement of the carriage across the adding field is completed and the cam 30

drops off of the left hand end of the plate 31 looking from the front of the machine. Extended from the shaft 36 is a short arm 39 connected by a link 40 to an arm 41 extended from the inner end of a comparatively short rock shaft 42 journaled in bearings 43 and 44, the former upstanding from the base of the carriage and the latter being secured to one of the carriage posts. Encircling the shaft 42 and having one end engaging the bracket 43 and its opposite end secured to a set collar 45 on the shaft, is a retracting spring 42' which tends to rotate the shaft 42 in the proper direction to retain the locking shaft 36 in the normal position, indicated in Figs. 3 and 5. At the end of the shaft 42 opposite the arm 41 is secured a bearing plate 46 for a longitudinally adjustable setting plate 47 having a longitudinal slot 48 for the reception of supporting screws 49 which retain the setting plate 47 upon the bearing plate 46, but permit the setting plate to have sufficient longitudinal movement to render the mechanism operative or inoperative in a manner to be described. At the end of the setting plate 47, which in effect is an arm of the rock shaft 42, is formed a lateral projection, lug, or abutment 50, which, when the automatic key locking mechanism is set, overlies a similar but oppositely disposed projection 51 on the rear end of a lever 52 fulcrumed on a bracket 53 extended from the back wall of the carriage casing, as shown in Fig. 8. The rear end of the lever 52 projects through a vertical slot 54 in the carriage casing and underlies an arm 55 secured by extending the arm 28 a considerable distance to the right of its fulcrum, viewed from the rear, the arms 28 and 55 producing a lever fulcrumed on the stud 26 and having its opposite ends adapted to contact with the register plate 31 and the lever 52 respectively.

It will now be seen that with the elements of the key locking mechanism in the positions shown in Figs. 5, 7 and 8, the carriage will advance across the column with the numeral keys unlocked and capable of operation to actuate the printing mechanism and also to actuate the adding mechanism, provided the key connecting mechanism is set for operation. As soon, however, as the retraction of the carriage is commenced the cam 20 riding up over the plate 31, see Fig. 4, will elevate the arm 28 and depress the arm 55, the latter in turn shifting the lever 52 which will raise the rear end of the setting plate 47 and thus rock the shaft 42 against the resistance of the spring 42' to rock the locking shaft 36 from the normal position shown in Fig. 3 to the locking position shown in Fig. 4 through the medium of the link 40 and the arms 39 and 41. Obviously, as soon as the carriage has been sufficiently retracted, the cam 20 will drop from

the plate 31 and the spring 46 will restore the key locking mechanism to normal unlocked position. The positions assumed by the parts during retraction of the carriage across the register and adding field, are fully shown in Fig. 4.

The setting means for the key locking mechanism.—The Elliott-Fisher machine here shown is intended, as heretofore suggested, for independent use as a typewriter as well as for typewriting and adding. It is because of this diversity of uses that the key connecting mechanism is provided with setting means by means of which the mechanism may be set for automatic actuation when the printing point moves into the column, or unset so that no connection of the keys with the adding mechanism will be effected, even when passing through the register or across the field or column.

Since my key locking mechanism has been designed as an adjunct of the combined typewriting and adding machine, and is intended to be used only when the carriage is retracted across the column during the typewriting and adding operation, it is also desirable to provide setting means for this key locking mechanism so that it will be effective for automatic operation only when the machine is set for addition. I therefore utilize the setting key 34 of the key connecting mechanism as a setting key for the key locking mechanism. To attain this end, it is merely necessary to provide the lever 32 at a point adjacent to its outer end with a depending bifurcated arm 56 engaging a projection 57 on the setting plate 47. Normally, that is to say, when the setting key 34 is in its rearward or total or non-adding position, shown in Fig. 3, the key connecting mechanism will be unset because the abutment roller 32 will occupy its forward position beyond the front end of the lever 24 and the key locking mechanism will likewise be unset because the setting plate 47 will occupy its rearmost position which will present the abutment 50 in rear of and out of coincidence with the projection 51 on the lever 52. Therefore, when the machine is unset for addition, the cam 30 will ride under the plate 31, as usual, during the forward movement of the carriage, but will not connect the keys with the adding mechanism, the positions assumed by the parts during such forward movement of the unset machine being shown in Fig. 3. Similarly, when the carriage of the unset machine is retracted, the cam 30 will ride up over the plate 31 and the arm 55 will operate the lever 52 of the key locking mechanism, but such operation will be ineffective to lock the keys because the projections 50 and 51 being out of coincidence, as shown in Fig. 3, the movement of the lever 52 will be idle and will not effect the transmission of motion to the locking shaft

36. If, however, the setting key 34 is moved rearwardly to the position shown in Fig. 4, both the key connecting mechanism and the key locking mechanism will be set for automatic operation during the forward and return movements, respectively, of the carriage across the column and register. This is true because the abutment roller 23 will be moved rearwardly into coöperative relation with the lever 24 and the setting plate 75 47 of the key locking mechanism will be moved forwardly to move the abutment 50 from the position shown in Fig. 3 to a position above the projection 51 on the lever 52, as shown in Figs. 1, 4 and 8. Therefore, as 80 the carriage of the set machine moves forwardly the cam 30 will ride under the register plate 31 and effect the operation of the key connecting mechanism to connect the keys 10 with the adding mechanism, as 85 shown in Fig. 1, but, as soon as the return movement of the carriage is commenced, the cam 30 riding up over the plate 31, will permit the disconnection of the keys in a manner well understood in the art and will operate the key locking mechanism in the manner already described and as shown in Fig. 4, to lock the numeral keys 10 against depression and thus prevent any operation whatever of the adding mechanism until the 90 carriage has been sufficiently retracted to permit the cam 30 to drop from the end of the plate 31 at which time the keys will be automatically unlocked by the retraction of the key locking mechanism under the influence of the spring 46.

It is thought that from the foregoing, the construction and operation of the mechanism constituting my invention will be clearly understood, but while the illustrated 105 structure is thought at this time to be preferable, I wish to expressly reserve the right to effect such variations thereof as may come fairly within the scope of the protection prayed.

What I claim is:—

1. The combination with adding mechanism and operating means therefor, relatively movable in a lateral direction to change their denominational relation and 115 also having relative retractile movement, of locking mechanism effective during the retractile movement only to prevent the actuation of the operating mechanism.

2. The combination with adding mechanism, operating keys therefor and intermediate operating connections, said adding mechanism and keys having relative movement in one direction to change their denominational relation and also having relative movement in a retractile direction, and key locking means rendered effective by said retractile movement and serving to lock the keys until such retractile movement has been completed.

3. In a combined recording and adding machine, the combination with adding mechanism, recording mechanism, and keys common to both the adding and recording mechanisms and operative to cause the recording mechanism to print both inside and outside of the adding field, and said recording and adding mechanisms having relative lateral movement to change their denominational relation and to permit recording both within and without the adding field, and also having relative retractile movement, and key locking mechanism rendered effective by the relative retractile movement of the adding and recording mechanisms to lock the keys during that part of the retractile movement in which the recording mechanism is disposed opposite the adding field.

4. The combination with an adding mechanism, a traveling carriage movable back and forth across the adding field, recording mechanism, and keys controlling the operation of both the recording and adding mechanisms, of key locking means ineffective during the movement of the carriage in one direction and effective, during the retraction of the carriage across the adding field, to prevent the operation of the keys.

5. In a combined recording and adding machine, the combination with adding mechanism, recording mechanism, and keys, of automatic key locking mechanism operative to lock the keys during the retraction of the recording mechanism across the adding field.

6. In a recording and adding machine, the combination with recording mechanism, adding mechanism, and keys, of a movable carriage, automatic key connecting mechanism operative to connect the keys and adding mechanism during the movement of the carriage in one direction, and automatic key

locking mechanism operative to lock the keys during the movement of the carriage in the opposite direction.

7. In a combined recording and adding machine, the combination with recording mechanism, adding mechanism, and keys normally disconnected from the adding mechanism, of automatically operated mechanism operative to alternately connect the keys with the adding mechanism and lock said keys.

8. In a combined recording and adding machine, the combination with recording mechanism, keys therefor, and adding mechanism normally disconnected from the keys, of key locking and connecting mechanism automatically operated to connect the keys with the adding mechanism and to unlock said keys and to lock the keys and disconnect the same from the adding mechanism.

9. In a recording and adding machine, the combination with recording mechanism, keys therefor and adding mechanism normally disconnected from the keys, of key connecting mechanism and key locking mechanism, said mechanisms including setting means common to both mechanisms.

10. In a recording and adding machine, the combination with recording mechanism, keys therefor, and adding mechanism normally disconnected from the keys, of automatically operated key connecting mechanism, automatically operated key locking mechanism, and a setting key common to both mechanisms.

In testimony whereof I affix my signature in presence of two witnesses.

WILLIAM L. DENCH.
